ELECTRICAL CONDUCTOR

Leo L. Weaver, Cranford, N. J., assignor to Western Electric Company, Incorporated, New York, N. Y., a corporation of New York

Application July 7, 1934, Serial No. 734,082

1 Claim. (Cl. 173—367)

This invention relates to electrical conductors and more particularly to multiple conductor cords or cables.

The cords used to connect a telephone receiver to the base of the instrument and the base to the bell box must be of sufficient length and flexibility, especially in the case of a desk telephone to permit of convenient use over a relatively wide area. At the same time in some cases it is preferable that these cords should not be in the way when the instrument is not in use. Similar considerations apply to the power cords used to supply current to lamps, flat irons, toasters and other electrical devices. Many devices in the form of variously coiled and shaped spring wires to be applied to or over such cords have been suggested.

An object of the invention is to provide a self coiling cord or conductor which is so constructed as to form itself into a neat and compact coil when not under tension without the application thereto of any extraneous means or device not normally included in the structure of such conductors or cords, and which shall nevertheless yield easily to tension tending to elongate the coil.

In one embodiment of the invention, one or more of the three metallic conductor strands of the customary telephone cord is made of some material such as a phosphor bronze alloy, which combines both satisfactorily high electrical conductivity and mechanical elasticity, and is formed as a flattened tape wound in a resilient helix or spiral with its curvature in the plane of its greatest transverse dimension. The conductors are insulated from each other and are bound together by suitably applied covers of braided textile strands or other approved means. Such a coiled flat conductor may be easily drawn out in the direction of its coil axis and tends to resume its compact coiled form when released.

Other objects and features of the invention will appear from the following detailed description of embodiments thereof taken in connection with the accompanying drawing in which the same reference numerals are applied to identical parts in the several figures and in which

Fig. 1 is a plan view of a length of three conductor cord constructed and formed in accordance with the invention;

Fig. 2 is a view thereof in side elevation;

Fig. 3 is an enlarged sectional view on the line 3—3 of Fig. 2;

Fig. 4 is a view similar to Fig. 1 of a modified form;

Fig. 5 is a view similar to Fig. 2 of another modified form;

Fig. 6 is an enlarged sectional view on the line 6—6 of Fig. 5, and

Fig. 7 is an enlarged sectional view of a third modification.

The embodiment of the invention disclosed in Figs. 1, 2, and 3 comprises three conductors 20, 21, and 22. These are flat tapes of rectangular cross section coiled in a resilient cylindrical helix 10 whose curvature is substantially in the plane of the tapes. The tapes are made preferably of a phosphor bronze alloy or other material having both satisfactory electrical conductivity and mechanical elasticity.

The middle tape 21 is individually covered with a braided protective and insulating sheath 23 of textile fibres, and the three tapes together are covered with a similar outer sheath 24.

Instead of coiling the cord in a helix as shown in Fig. 2, it may in some cases be preferable to coil it as a flat resilient spiral as shown in Fig. 4. In either case the coiled form is held and sustained by the coiled flat conductors and not by any added member.

Figs. 5 and 6 discloses a modified form of the invention in which there is only one conductor in the cord and in which the cross section of the conductor is elliptical or oval and is formed into a helix with the principal curvature in the plane 30 of the greatest cross section dimension of the conductor.

A cord or cable made and formed in accordance with the invention may have any number of conductors associated together provided that one of the conductors be elastic and have a cross section of greater dimension in one of two mutually perpendicular directions than in the other, so that if the cord be formed as a coil with its curvature in the plane of the greater cross section dimension of the flattened conductor, it will flex easily across that plane but will resist flexure in the plane.

Thus Fig. 7 is a cross section of a cord embodying the invention in which a single flat tape conductor 21 is combined with two ordinary round or stranded conductors 120 and 122 and the whole may be coiled in a resilient spiral or helix with the curvature in the plane of the tape 21.

One advantage of the construction disclosed in Figs. 1, 2, and 3 is the saving in covering material. The flat tape-like conductors enclosed in the sheath 24 are held thereby against relative lateral displacement, and in particular conductors 20 and 22 cannot slide around conductor 21 and make contact with each other. Hence for mu-

tual insulative separation of the three conductors it is necessary only to cover the middle conductor 21 individually, whereas if all three were circular in cross section, no one could be relied upon to 5 separate the other two. The same is true of the construction shown in Fig. 7.

In the disclosure above it is suggested that the conductive strands 20, 21, and 22 be made of phosphor bronze. This is a preferred construction 10 since such alloys are at the same time highly electrically conductive and also highly mechanically elastic. The invention is not, however, confined to this material as in some instances other materials such as spring brass, some spring steels, 15 certain nickel alloys such as monel, nichrome and the like, and for some uses hard drawn alloys of aluminum could be used.

For simplicity and clarity of statement the phrase "substantially flat" as applied to the cross 20 section of a conductor will hereinafter be used to mean a cross section greater in one direction than in any other, and thus will include oval, elliptical, rectangular but not square, rhombic or rhomboidal cross sections and the like. Also the 25 phrases "coiled in the plane of the conductor" or "coiled in the plane of the strand" will be similarly used to mean coiled so that the curva-

ture of coiling is substantially in or parallel to a plane passing through the conductor or strand in the direction of the greatest dimension of the cross section of the conductor or strand.

The embodiments of the invention herein disclosed are illustrative merely and may be modified and departed from in many ways without departing from the spirit and scope of the invention as pointed out in and limited solely by the appended claim.

What is claimed is:

An electrical conductor cord comprising three strands each a unitary combined conductor and coiling spring and each of material both electrically conductive and mechanically elastic and 15 each formed with a substantially flat cross section and the three cross sections being mutually parallel, a sheath of insulating material on the middle strand, and a sheath of insulating material over the whole, the whole conductor cord being coiled 20 in the plane of the flat strands, whereby the coiled conductor is easily elastically deformable under stress along the axis of the coils thereof and tends to return to its coiled form when released from stress.

LEO L. WEAVER.
